(57) **CLAIM**

What is claimed is the ornamental design for an absorbent pad, as shown and described.

DESCRIPTION

FIG. 1 is a front view of my new design;

FIG. 2 is the left side elevational view thereof, the right side elevational view being a mirror image thereof;

FIG. 3 is a back view thereof;

FIG. 4 is an enlarged fragmentary portion of the front view thereof as indicated in FIG. 1;

FIG. 5 is an enlarged, partial fragmentary, cross sectional view thereof taken along line 5-5 in FIG. 4; and,

FIG. 6 is an enlarged, partial fragmentary, cross sectional,

perspective view thereof taken along line 6-6 in FIG. 4. The broken line showing of an absorbent pad are included for the purpose of illustrating environment and forms no part of the claimed design.

1 Claim, 3 Drawing Sheets
